UNITED STATES PATENT OFFICE.

CHARLES H. CARTLIDGE, OF LA GRANGE, ILLINOIS.

REINFORCED CONCRETE PIPE.

No. 889,440.

Specification of Letters Patent.

Patented June 2, 1908.

Application filed October 31, 1906. Serial No. 341,453.

To all whom it may concern:

Be it known that I, CHARLES H. CARTLIDGE, a citizen of the United States, residing at La Grange, in the county of Cook and State of Illinois, have invented certain new and useful Improvements in Reinforced Concrete Pipes, of which the following is a specification.

My invention relates to reinforced concrete pipes, especially to concrete culvert pipes; and has for its object to produce such a pipe in which the minimum amount of material is combined to produce a pipe of maximum strength.

To this end my invention consists in the combinations and details hereinafter set forth and claimed.

In the accompanying drawings—Figure 1 is a transverse sectional view of my improved pipe upon the line 1 of Fig. 2. Fig. 2 is a side elevation, partly in section, upon the line 2 of Fig. 1. Fig. 3 is a longitudinal sectional elevation showing a modified form of reinforcement.

As is well-known there are on many railroads a great number of wooden, pile and trestle bridges which cross streams of drainage sufficiently small to permit the use of a comparatively small culvert opening. It has been hitherto impracticable to replace such temporary structures with earthen embankments, because of the high cost of such culverts as have been in use,—the earth work in the majority of cases being a comparatively small proportion of the total expense required.

One object of my invention is to produce a concrete culvert pipe in which a minimum amount of material is used, at the same time possessing requisite strength so that the expense of replacing temporary bridges of timber by culvert and earthen embankments may be greatly lessened. As is well-known concrete is relatively strong in compression, while its value in tension is not to be relied upon, so that a pipe having the requisite amount of material to resist compression strains would not resist tensional strains to the required degree. It becomes necessary, therefore, to so reinforce a pipe having only the requisite amount of concrete to resist compression strains, that it will resist also the tensional strains to which it may be subjected.

In carrying out my invention I provide a pipe having a body of concrete *a*, and em-

bedded in this pipe I provide reinforcing bands of steel *b* and *c*, the bands *b* being in the form of rings arranged transversely of the pipe and the band *c* being in the form of strips running longitudinally of the pipe. By reference to Fig. 1, it will be observed that the rings *b* are so embedded in the concrete forming the body of the pipe as to be nearer the inner surface of the pipe at the top and bottom portions thereof and nearer the outer surface of the pipe at the opposite diameter—that is, the reinforcing bands occupy the position which will relieve the concrete of its tensile stress under average conditions of load. This result may be obtained either by forming the reinforcing bands in circular form and the concrete forming the body of the pipe slightly elliptical—as indicated in Fig. 1—or, as is obvious, the body of the pipe may be made circular and the reinforcing bands elliptical. I prefer, however, to construct the pipe, as shown in my drawing, with the concrete portion slightly elliptical or having one of its axes elongated, and the reinforcement circular, since by this means the reinforcement is placed in position which will relieve the concrete of its tensile stress, and at the same time owing to the fact that the pipe has a greater diameter upon one axis, a means is provided whereby the sections of the pipe may be quickly and readily laid with the reinforcement occupying its proper position. If the pipes were made circular, it would be necessary to place thereon some distinguishing marks by which to indicate the proper position of the pipes when laying the same.

Longitudinal bands *a* are arranged approximately at the center of the mass of concrete, hence—as shown in Fig. 1—some of them pass outside the transverse bands and others inside the transverse bands. A reinforcing pipe made as above described possesses great tensile strength, although a minimum amount of concrete is used. Instead of forming the transverse reinforcement of separate rings,—as shown in Fig. 2—I may form this reinforcement of a continuous strip of metal in the form of a spiral,—as shown in Fig. 3—the construction otherwise being the same in the two forms. One end of each section pipe is formed with a bell mouth *a'* and the longitudinal reinforcements *c* are bent downwardly as at *c'* to form, in conjunction with the rings *c*, a

reinforcement at the end of the pipe. I am thus enabled to form a culvert of sections, possessing flexibility under heavy embankments—a feature which continuous culverts of any material do not possess. The bell joint provides for the closure of any opening made by settlement and prevents extensive leakage. At the same time it affords no resistance to the curvature of the pipe as a whole. This curvature takes place whether the pipe is built as a continuous piece or in sections, but when built as a continuous structure, it invariably results in breakage of the culvert.

15 The advantages of my improved pipe will

be readily appreciated without further description.

I claim:

A conduit comprising an elliptical body portion of initially plastic material, and a 20 circular reinforcement embedded within the body portion, whereby the reinforcement lies adjacent the inner surface of the body portion at its greater axis and adjacent its outer surface at its shorter axis.

CHARLES H. CARTLIDGE.
